SNOWSHOE

Frederick T. Paden, Collingwood, N. J.

Application October 10, 1950, Serial No. 189,465

2 Claims. (Cl. 36—4.5)

(Granted under the act of March 3, 1883, as amended April 30, 1928; 370 O. G. 757)

1

The invention described herein, if patented, may be manufactured by or for the Government for governmental purposes without the payment to me of any royalty thereon.

This invention relates to snowshoes and in general aims to provide a snowshoe suitable for military use and having the following characteristics, among others:

- (1) Light weight;
- (2) Waterproof and non-warping;
- (3) Superior strength and durability;
- (4) Reasonable cost;
- (5) Capable of manufacture on a mass production basis;
- (6) Minimum absorption of heat from the sun;
- (7) Usable with various types of foot bindings;
- (8) Permanently white to be inconspicuous against snow;
- (9) Construction adaptable to any design or shape of snowshoe.

In the accompanying drawings showing several embodiments of the invention,

Fig. 1 is a top plan view of a snowshoe of the "bear paw" shape or design;

Fig. 2 is a side elevation of the same;

Fig. 3 is a top plan view of a snowshoe of the "trail" design, shown on a smaller scale;

Fig. 4 is a side elevation of the snowshoe of Fig. 3;

Fig. 5 is a fragmentary plan view, scale full size, of the preferred web which forms the body of the snowshoe of Figs. 1-4 inclusive;

Fig. 6 is an exploded view in perspective of a laminated snowshoe embodying the invention, part of the reinforcing for the toe hole being omitted.

Referring further to the drawings, either design of snowshoe shown in Figs. 1-4 inclusive comprises a rigid frame, a perforated web enclosed by and secured to the frame, and reinforcements for the web secured to the web and the frame.

The preferred frame is of metal, preferably a bent tube of aluminum, magnesium alloy or steel, which will be non-warping and non-water-absorbent. The tubular "bear paw" frame 20 of Figs. 1 and 2 preferably has its ends abutted and welded (not shown) to form a closed loop. The elongated "trail" frame 21 of Figs. 3 and 4 is a loop with its forward end bent upwardly as shown and with its rear extremities extending side by side and welded, riveted or otherwise secured together. In cross section the frames 20 and 21 may have a number of shapes such as round, oval,

5

square, oblong, channel-shaped, H-shaped, etc. A metal frame is readily bent when formed, and the upturned toe of the "trail" model (Fig. 3) as well as of the "trapper" model (not shown) is provided without difficulty. Any metal frame is easily formed on its underside with ridges or protuberances (not shown) to increase the "bite" or grip of the snowshoe on crusted snow or other slippery surfaces.

10

The mat or web 25 has numerous perforations or openings 25a (Fig. 5) which are preferably diamond-shaped, although they could be round or any other shape. These perforations may be cut from a sheet from which the web 25 is formed or they may be formed when the web is made by projections upstanding from a form. Diamond-shaped perforations are more desirable because they leave a greater amount of material between the openings, which results in greater strength for the web. A large number of perforations are desirable to lessen the weight of the snowshoe and to permit snow on top of the snowshoe to sift through the perforations. The web may be of woven glass fiber cloth or a non-woven matting of glass fibers, or it may be of stout cloth made from cotton, rayon, nylon, fortisan or orlon, or other fibers of the same general characteristics. The web should be formed and cured separately to provide an easily handled sub-assembly which is assembled with and then riveted or otherwise secured to the tubular frame as already described. A phenolic resin, a polyester resin, polystyrene or similar resins may be used to fortify and stiffen the web, which when cured is a tough, thin, slightly flexible, waterproof sheet having a thickness of between one sixteenth and one thirty-second of an inch, in the preferred form. Heat and pressure will of course be used when the resin is such that it cannot be cured properly otherwise. White pigments such as titanium oxide, zinc oxide, zinc sulphide or white lead (basic lead carbonate) are desirably incorporated in the selected resin prior to curing, thereby giving permanent whiteness to the web, thus contributing to camouflage of a soldier and his equipment when moving over a snowfield. Permanent whiteness may also be imparted to the frame by white coatings or wrappings or by white fillers incorporated in plastic filaments afterwards woven into cloth-like fabrics. An all-white snowshoe made as described will reflect most of the sun's rays and thus will not be highly heated thereby; moreover, it will be a poor conductor of heat and hence more desirable for use in very

2

Any true snowshoe must have a toe hole for receiving the toe of the boot or shoe worn by the user when the user walks in snow. Such toe holes are shown at 52 in Fig. 1 and at 53 in Fig. 3. To reinforce the web 25 adjacent the toe holes, tapes or strips of some woven material such as cotton or glass fiber cloth extend around the toe holes, being bonded or otherwise secured, thus giving the desired strength and stiffness to the web at the area where most of the stresses are imposed. As many as four thicknesses of tapes may be used.

In lieu of woven tapes or strips, metal reinforcements may be employed. The metal may be stranded metal cable, thin steel strap or aluminum or magnesium alloy strap with the ends bent around the frame and welded or riveted, or with the ends riveted to flanges on the frame, or directly welded at the ends to the metal frame.

Now turning to Fig. 6, another way of making the snowshoe is there shown. In this instance the frame, preferably of a one-piece molded plastic construction, but of all metal construction if desired, comprises an outer frame 60 having integral reinforcing crosspieces 61, 62, 63 and other reinforcing strips 64, 65 extending lengthwise and joined to crosspieces 62, 63. Two laminations 66, 67 each stamped from a sheet of woven or matted material such as Fiberglas, each having registering perforations 68 and rectangular toe holes 69, are adapted to be assembled with and bonded to either side of frame 60 and its reinforcements to make a unitary body of the necessary qualities. More than two laminations may of course be bonded within the frame to form the web. The toe hole formed in the completed snowshoe by the registered holes 69 may be reinforced in the manner described above, as will be understood without further illustration.

From the foregoing it will be apparent that the above listed desiderata are realized by the described snowshoe constructions.

However, one feature may require elucidation: 45 minimum absorption of the sun's heat. This is of importance in snowshoes because on a sunny day with the air temperature below freezing a

metal snowshoe may absorb sufficient solar heat to melt snow lying on top of it. This melted snow will, however, freeze very quickly when a shady area is reached or when the sun is obscured or goes down, thus making a layer of ice on the snowshoe. Repetition of this melting and freezing may build up a heavy ice layer which may so fatigue the wearer that further walking becomes difficult. The described constructions will absorb little solar heat so that ice will not build up in layers on top of the snowshoe. Snowshoes embodying the invention will weigh materially less than prior art snowshoes of the same size, and will be permanently white regardless of wear.

What I claim is:

1. A snowshoe comprising an open frame, a web secured to the frame, and reinforcements secured to and extending across the opening in the frame; said web comprising a plurality of superposed perforate layers of material; and means for bonding said layers together and to the reinforcements, with at least two of said layers being on opposite sides of the reinforcements.
2. A snowshoe comprising an open rigid frame; a plurality of spaced reinforcements secured at their ends to the frame and extending transversely across the opening in the frame; and a perforated web comprising at least two layers, the layers being on opposite sides of the reinforcements and being bonded to the reinforcements and also to the frame to make a unitary body, the web having a toe hole and some of the reinforcements bordering opposite sides of the toe hole.

FREDERICK T. PADEN.
